UNITED STATES PATENT OFFICE

FRANCIS W. COOPER, OF MONTREAL, QUEBEC, CANADA, ASSIGNOR TO STEAD RAIL ANCHORS INCORPORATED, OF WILMINGTON, DELAWARE, A CORPORATION OF DELAWARE

RAIL ANCHOR

Application filed February 8, 1926, Serial No. 86,916. Renewed May 31, 1930.

This invention relates broadly to improvements in rail anchors and more particularly to one-piece rail anchors.

The primary object of the invention is to provide a one-piece rail anchor applicable to rails of different sizes and capable of being adjusted on a rail to compensate for wear or for relaxation of the anchor.

A further object is to provide a substantially symmetrical or double-ended anchor which will be reversible and will in consequence have at least double the life of a single-ended anchor.

A still further object is to provide an anchor capable of reversal to relieve certain localized stresses therein, thus giving the metal opportunity to recover from the fatigue effects of a constant stress.

Another object is to provide a rail anchor having very large bearing surface for abutment against a tie.

Still another object is to provide a one-piece rail anchor which will if either slewed or canted from its normal relation to a rail, by pressure against a tie, increases its grip upon the rail.

Additional objects and the advantages of the invention may be ascertained from the following description and the accompanying drawing.

Various forms of one-piece rail anchors have been proposed and several are in use. In general, these anchors each comprise a body hooked at one end to embrace one flange of a rail base and differently formed at the opposite end to press against the edge of the other base flange. The opposite ends of such anchors being differently formed, neither end will perform the functions of the other end. Usually the hooked ends of such anchors are more severely stressed than the other ends and, if the stress develops into a strain usually manifested by opening of the hooks, the anchors lose their grip on the rail and cannot, ordinarily, be retained in service.

According to the present invention, the anchor comprises a body carrying two substantially similar end portions for engagement respectively with the two flanges of a rail base, the said end portions being so

formed that each end is capable of engaging a rail base flange in two entirely different ways. If either end becomes fatigued and develops strain, the anchor may be reversed so that the unstrained end performs the function of the strained end and vice versa. In greater detail, the anchor preferably comprises a bar of resilient material, such as spring steel, bent at its ends to form mutually facing substantially similar hooks, each adapted to embrace one flange of a rail base from above and below, and each having a series of alternated shoulders and seats designed for successive abutting relation with the edge and lower surface of a base flange and designed to adapt the anchor to rails of different sizes. When the anchor is forcibly applied to a rail base, one end is in embracing relation with one base flange and is much more severely stressed than the other end, which is in abutting relation with the edge and bottom of the other flange. If that end of the anchor which is embracing a rail flange shows signs of fatigue the anchor may be driven more tightly on the rail so as to engage another shoulder and seat or alternately, the anchor may be removed from a rail and reversed with the end which formerly abutted the flange now in flange embracing position, and vice versa. That end of the anchor which is in flange abutting position depends below the rail base and forms an abutment to engage a tie. The arrangement is such that only the hook which is in flange embracing position is stressed, the other hook being completely relaxed, so that upon reversal of the anchor the hook which was giving evidence of fatigue will be relieved of service stresses and, even if it has been badly strained, will function perfectly in its new capacity of tie abutting member.

The type of anchor forming the subject of the present invention is characterized by provision of the hooks aforementioned on opposite sides of the shank or body. Another type of anchor exists having two similar end hooks each capable of engaging a rail base flange in two different ways. This other type of anchor is distinguished from the type herein described by the location of its hooks

both on the same side of the shank, and is covered in my Patent No. 1,618,577, granted February 22nd, 1927.

In the accompanying drawing, which illustrates in two figures certain combinations of four modifications of the type of anchor herein dealt with, but to which modifications and combinations thereof or any or all of the details thereof the invention in its broad aspects is by no means limited, the same being disclosed for explanatory purposes and without limitative intent,—

Fig. 1 is a plan view of an anchor formed according to the present invention as seen in position on a rail.

Figs. 2 ad 3 are side elevations illustrating various modifications of the type of anchor herein dealt with, each being in plan, substantially as shown in Figure 1.

Fig. 4 is a plan view illustrating a further modification.

Referring more particularly to the drawing, 11 and 12 designate the base flanges of a rail and 13 and 14 designate the substantially similar end hooks of a rail anchor shown as engaging the flanges 11 and 12, respectively, the said hooks being connected by a body or shank 15 extending beneath the rail base, transversely thereof. The hooks are each adapted to embrace a flange of the rail base and are each additionally provided on the back with a shoulder to abuttingly engage the edge surface of a base flange. As will be seen, the hooks are formed on opposite sides of the shank 15, so that when either hook is in operative flange embracing relation with a rail the other hook is inverted beneath the rail and engages the edge surface of the second flange thereof by means of the shoulder.

The inner surface 16 of the tip of each hook is adapted to bear, substantially flatwise, on the sloping upper surface of a base flange, while the inner surface 17 of the back of each hook is adapted to bear on the bottom surface of a base flange. While in theory there will be, in the case of the two modifications shown in the drawing, only a line bearing between the curved surface 17 and the flange bottom, there will be, for all practical purposes, an appreciable area of bearing surface. The bearing surfaces 17 are formed, in each of the modifications shown, on portions of the anchor projecting into the hooks intermediate the tips and throats thereof and resulting from the provision of slight bends, as at 18, between the shanks and hooks and in the reverse directions to the hooks' bends. The opening of each hook is initially too little to fully accommodate the rail flange for which the hook is intended, so that in application to a rail the flange embracing hook will be forced slightly more open, as indicated by comparison of the dotted and full lines of the hook 13 in Figure 2, the dotted lines indicating the relaxed condition of the

hook before application. Because of downward pressure of the hook tip on a base flange, which will result from forcible entry of the flange, the tips of the hook are preferably turned sufficiently outward to avoid edge bearing on the flange, such manner of engagement rendering application of the anchor difficult. The back of each hook is provided with one or more shoulders 19 for abutment against the edge of a rail base flange, and there is provided inwardly of each such shoulder a bearing surface 20 for engagement with the under surface of a rail base flange. The shoulder or shoulders of each hook are located a distance from the throat of the other hook somewhat greater than the width of the base of the rail or rails, for which the anchor is adapted, so that when the anchor is in position on a rail one edge of the rail base will be in engagement with a shoulder 19 and the other edge will be spaced from the root of the other hook. Figures 2 and 3 present two modifications in respect to the shoulders 19 and seats 20. In Figure 2, the shoulders and seats are formed by pressing or cutting the outwardly bulging backs of the hooks or in some other way formed within the normal lines of curvature of the hook backs. In Figure 3 the shoulders are formed by reason of projections 21 beyond the normal lines of curvature of the hook backs. The seats 20 in the modification may be merely the normal surfaces of the hook backs, as shown, or specially formed seats 20, such for example as in Figure 2, may be incorporated with the projection type of shoulder. The modification of Figure 2 further discloses the provision of a plurality of shoulders 19 and seats 20 on each hook for the purpose of adapting the anchor to a variety of rail base widths or a variety of base flange thicknesses, or both. Obviously, a plurality of shoulders and seats at each end of the anchor may be applied to shoulders provided after the manner shown in Figure 3.

If it is deemed advisable to depart in a small measure from the feature of exact similarity of the hooks, but without abandoning the feature of reversibility, which is the object of the similar hooks, one hook can be initially formed slightly more open than the other and the shoulders located slightly differently as between the two hooks, so as to adapt the anchor to a wide range of variations in rail base dimensions. In the case of such alternative formation, the feature of reversibility of the anchor will be partially but not wholly sacrificed, the anchor being still reversible on rails of intermediate sizes but probably not reversible on rails the dimensions of which are the extremes of the range covered.

Figures 2 and 3, in addition to disclosing different modifications of hook formation,

also disclose two modifications of shank formation, Figure 2 showing a straight shank and Figure 3 an undulating curved shank, designated 15°. It is to be understood that 5 the invention is not in any way confined to the combinations of shank and hook formation illustrated, as these modifications may be otherwise combined with one another or with additional modifications not herein 10 shown. The curved shank has the advantage of resiliency which may serve to relieve the hooks of some stress in operation, while the straight shank has the advantage of being more easily manufactured.

15 In Figure 4, there is shown a further modification, applicable in combination with any of the other modifications herein shown or in combination with other modifications, and which comprises offsetting the anchor so that 20 the hooks thereof, instead of lying in the same plane as the shank, lie in substantially parallel planes slightly out of parallel with the plane of the shank. While the offset is shown as occurring in the shank, so as to 25 position the hooks parallel with the side of a tie, it will be understood that it is not confined to the exact location or formation shown, but may be otherwise effected.

The manner of applying the anchors to a 30 rail and removing the same from a rail is the same for all modifications shown and is extremely simple. The anchor is passed transversely under a rail as closely as possible in contact with the tie against which the anchor 35 is to bear, and with the hook of the leading end downwardly turned, so that the hook at the trailing end passes into embracing engagement with one flange of the rail base. The opening of the hooks being too small for 40 full entry of the base flange, as already stated, the flange wedges between the surfaces 16 and 17 of the trailing hook and arrests manual movement of the anchor before the appropriate shoulder 19 at the leading end passes 45 the edge of the other flange. Considerable force must be exerted to complete the advance of the anchor to operative relation with the rail, such force being usually applied with a hammer by striking toward the rail on the 50 outer end of the trailing hook. During the forcible advance of the anchor the embraced flange spreads the hook (13) open to a relatively greater extent than shown in full lines, Figure 2, due to the fact that the shank is at 55 a greater angle to the bottom of the rail base than shown, by reason of the back of the shoulder at the advancing end holding the shank away from the rail base. It will be noticed that the bearing surface 16 of the hook 60 tip is nearer the central vertical plane of the rail than the bearing surface 17. This causes the anchor to act as a lever fulcrumed on the bottom of the rail base at the bearing surface 17 and, at its advancing end (14) pressing 65 upwardly against the rail base. When the

advance of the anchor is completed and the shoulder 19 passes the edge of the flange, this upward pressure causes the leading end of the anchor to rise so that the shoulder 19 passes into engagement with the edge surface 70 of the flange (12). The rise is accompanied by a swing of the anchor around its fulcrum point 17 with consequent relief of hook tension and contraction of the hook (13) to the position shown in full lines, Figure 2. The hook is still under considerable tension and operates to hold the opposite end of the shank up against the rail base bottom, so that the seat 20 presses against the rail base bottom and the shoulder 19 is held against dropping 75 out of engagement with the flange edge. This engagement of the shoulder against the flange edge operates to hold the anchor against retreating movement under influence of the hook contracting upon the tapering base flange 80 (11).

The anchor is released by striking downwardly and toward the rail on the end of the inverted hook (14), so as to disengage the shoulder 19 from the flange edge and drive 85 the shoulder under the flange. The anchor may then be easily driven off the rail, the movement being assisted by contraction of the flange embracing hook.

The excess opening of the flange embracing hook during application of the anchor serves to automatically test the hook for proper temper and freedom from serious flaws. If the hook contracts properly and tightly grips the flange after the shoulder 19 is in operative 90 position, it indicates that the hook is serviceable and has successfully withstood the test. If, by reason of straining of the hook in application, the grip of the hook on the base flange is not as intense as desired, the grip 95 may be increased, if the width of rail base permits, by further advancing the anchor until the second shoulder 19 engages the flange edge and the flange embracing hook is increasingly tensioned by the flange being relatively forced farther into it. This take-up feature, which is not intended for use in an initial application of the anchor, is, however, intended for use after a period of service such 100 that the flange embracing hook has partially lost resiliency due to fatigue of the metal, and as an alternative to reversing the anchor. If the flange embracing hook should for any reason lose the tenacity of its grip on the flange, the anchor may be removed and reversed, that is, turned end for end and upside down and then reapplied, so as to bring the other hook into flange embracing position and the strained or fatigued hook into 105 unloaded position under the rail base. When 110 thus relaxed, the metal of the hook may in time recuperate to an extent enabling the hook to be serviceable after a second reversal returning the hook to its original flange embracing position. The provision of a series 115 120 125 130

of shoulders 19 also and primarily serves to adapt the anchor to a variety of rail base widths and thicknesses, either alone or in combination with variation of hook opening.

5 The feature of multiplicity of shoulders is not confined to the modifications herein disclosed but may be applied to other modifications.

When the anchor is in position on a rail and 10 in engagement with a tie, it functions to hold the rail against creeping in the direction of its length, by reason of its grip on the rail, which causes it to thrust against the tie and restrain the rail to an extent equal to the gripping force exerted.

15 The principal portion of the anchor engaging the tie, and in the case of pole ties the only part, is the inverted hook at the opposite end of the anchor from the flange embracing hook. Thus, the force urging the rail to creep is applied to one end of the anchor and tends to slew the anchor out of its normal position at right angles to the rail.

20 The anchor grips the rail across its width by both flanges and, since the anchor cannot 25 elongate to accommodate itself to a greater distance angularly across the rail, any slew ing movement or tendency serves only to draw the flange embracing hook farther in on the embraced flange, thus increasing the ten-

25 acity of its grip. Pressure of the inverted hook against a tie produces also a canting or tipping tendency under which the anchor tends to rotate about the longitudinal axis of the shank. The force is in this case transmitted 30 from the tie engaging hook as a torsion stress in the shank to the flange engaging hook and serves to further increase the grip thereof on the base flange.

While the foregoing description infers 40 manufacture of anchors of the various modifications discussed by bending the same from bars of metal, rectangular in cross-section, it is to be understood that the invention is not by any means confined to this method 45 of manufacture or to material of the cross-section shown, but extends to the use of metal of other cross-sections and the employment of other methods, such as punching or shearing from flat 50 bars or sheets or even forging from billets or blanks, or any combination of these methods with one another or with other methods. It is, however, at the present time, deemed preferable to employ the bending method 55 combined with a stamping or pressing operation to form the shoulders 19 and seats 20, since these present no difficulties and enable the anchors to be quickly, easily and inexpensively made without waste. The bending 60 method has the further advantage that the anchors may easily be made of the thickness necessary to have rigidity in canting and the necessary length of bearing in the direction of rail length to ensure security of grip on a rail and increase of such grip in canting.

While the anchor is illustrated as flat, and is preferably flat, it may be otherwise formed, for example as shown in Figure 4.

In addition to the advantages already mentioned, it may be pointed out that the double 70 hook construction is inherently resilient and capable of withstanding vibration without losing its grip on a rail and without creeping, and is moreover capable of contracting upon a rail to compensate for any wear which 75 may occur. All modifications of the anchor are extremely sturdy and are of such design that they cannot be improperly applied.

Many variations of minor detail may be made without departing from the spirit of 80 the invention and all such variations, modifications, substitutions and changes whatsoever, as fall within the scope of the appended claims are to be deemed as included in the invention.

Having thus described my invention, what I claim is:—

1. A rail anchor including a body and a hook at each end thereof, said hooks being respectively on opposite sides of the body, the 55 body being formed at each end within the hooks to present a single area for engagement with the under side of the rail base relatively short in the direction of rail base width.

2. A rail anchor including a body and a 95 pair of hooks, one at each end thereof, each formed to embrace a rail base flange and to present a single area for engagement with the under side of the rail base, relatively short in the direction of rail base width and spaced 100 inwardly from the edge of the rail base, and also formed with a plurality of shoulders adapted one at a time to abuttingly engage a rail base flange.

3. A rail anchor including a body and a 105 pair of hooks, one at each end thereof, one of said hooks being adapted to contractingly embrace one flange of a rail base and to present a single area for engagement with the under side of the rail base, relatively 110 short in the direction of rail base width and spaced inwardly from the edge of the rail base, and the other of said hooks to be thereby disposed below the other flange of such rail base in position to thrust against a tie, 115 said second hook being shouldered at a plurality of points to abuttingly engage the edge surface of said second flange and to hold the first hook against disengagement 120 from the first flange, the points of engagement of the first hook with the upper and lower surfaces of the first flange being at such different distances from the flange edge that the contractile action of the hook operates to urge the anchor to movement such as will engage a shoulder of the other hook with the flange edge and maintain such engagement, each of said hooks being substantially similarly formed and capable of functioning as stated.

4. A rail anchor comprising a body and a pair of hooks one at each end thereof, one adapted to embrace one flange of a rail base and to present a single area for engagement with the under side of the rail base, relatively short in the direction of rail base width and spaced inwardly from the edge of the rail base, and the other being formed with a plurality of shoulders for abutment singly against the edge surface of the other rail base flange, whereby the anchor is applicable to rails of different base dimensions. 5. A rail anchor comprising a body and a pair of hooks, one at each end thereof, one adapted to embrace one flange of a rail base and to present a single area for engagement with the under side of the rail base, relatively short in the direction of rail base width and spaced inwardly from the edge of the rail base, and the other being formed with a plurality of shoulders for abutment singly against the edge surface of the other rail base flange, whereby the anchor may be engaged successively in a plurality of relations to a rail to compensate for decreasing grip on the rail. 6. A rail anchor comprising a body and a pair of hooks, one at each end thereof, one adapted to embrace one flange of a rail base and to present a single area for engagement with the under side of the rail base, relatively short in the direction of rail base width and spaced inwardly from the edge of the rail base, and the other being formed with a plurality of shoulders for abutment singly against the edge surface of the other rail base flange, whereby the anchor is applicable to rails of different base dimensions, said hooks each being adapted for both embracing and abutting engagement with a base flange as stated, but at different times. 7. A rail anchor comprising a body and a pair of hooks, one at each end thereof, one adapted to embrace one flange of a rail base and to present a single area for engagement with the under side of the rail base, relatively short in the direction of rail base width and spaced inwardly from the edge of the rail base, and the other being formed with a plurality of shoulders for abutment singly against the edge surface of the other rail base flange, whereby the anchor is applicable to rails of different base dimensions, said hooks being substantially similar whereby each is adapted for both embracing and abutting engagement with a base flange as stated, but at different times. 8. A substantially symmetrical rail anchor including a pair of hooks projecting from opposite sides thereof, one at each end thereof, and a shank extending between the hooks offset intermediate its ends to locate the hooks in non-aligned planes. 9. A rail anchor comprising a body and a pair of substantially similar hooks project-
- ing from opposite sides of the body, one at each end of the body, the body being offset intermediate its ends to locate the hooks in substantially parallel planes. 10. A rail anchor comprising a body and a pair of substantially similar mutually facing hooks projecting from opposite sides of the body, one at each end of the body, the body being offset intermediate its ends to locate the hooks in non-aligned planes whereby when either hook is positioned flat against a tie the other hook will be spaced from the tie. 11. A rail anchor comprising a body and a pair of substantially similar hooks, one at each end of the body, the body being offset intermediate its ends to locate the hooks in non-aligning planes, the amount of such offset being less than the thickness of the anchor. 12. A rail anchor comprising a body and a pair of substantially similar hooks, one at each end of the body, the body being offset intermediate its ends to locate the hooks in non-aligning planes, the amount of such offset being less than half the thickness of the anchor. 13. A rail anchor comprising a body and a pair of hooks, one at each end of the body and on opposite sides of the body, the body being offset intermediate its ends to locate the hooks in non-aligning planes. 14. A rail anchor including a body hooked at one end to embrace one flange of a rail base and to present a single area for engagement with the under side of the rail base, relatively short in the direction of rail base width and spaced inwardly from the edge of the rail base, and formed at the other end with a plurality of shoulders adapted for engagement singly with the other flange of a rail base, whereby the anchor is adaptable to rails of different base widths and flange thicknesses and capable of adjustment on a rail to compensate for decreasing grip on the rail, the shouldered end of said anchor including a portion depending below a rail base in position for abutment against a tie. 15. A rail anchor including a body hooked at one end to embrace one flange of a rail base and to present a single area for engagement with the under side of the rail base, relatively short in the direction of rail base width and spaced inwardly from the edge of the rail base, at locations spaced inwardly from the edge of the flange and stepped at the opposite end, each of the steps being adapted to engage and press against the outer edge surface of the other flange while the adjacent step presses against a lateral surface of the same flange. In witness whereof, I have hereunto set my hand.

FRANCIS W. COOPER.

CERTIFICATE OF CORRECTION.

Patent No. 1,914,684.

June 20, 1933.

FRANCIS W. COOPER.

It is hereby certified that the above numbered patent was erroneously issued to "Stead Rail Anchors Incorporated, of Wilmington, Delaware, a corporation of Delaware", as assignee of the entire interest in said invention, whereas said patent should have been issued to "The Stead Rail Anchor Company, Limited, of Montreal, Quebec, Canada, a corporation of Canada", as shown by the records of assignments in this office; and that the said Letters Patent should be read with this correction therein that the same may conform to the record of the case in the Patent Office.

Signed and sealed this 29th day of August, A. D. 1933.

M. J. Moore.

Acting Commissioner of Patents.
